ROTATOR

Andrew F. Deming and Emmor V. Schneider, Alliance, and Richard H. Jordan, Mansfield, Ohio, assignors, by mesne assignments, to The Alliance Manufacturing Company, Division of Consolidated Electronics Industries Corporation, Alliance, Ohio, a corporation of Delaware

Application June 12, 1953, Serial No. 361,324

19 Claims. (Cl. 343—766)

The invention relates in general to rotating devices and more particularly to remote controlled rotator units, especially for antennas wherein the remote control unit and the rotator unit are interconnected by only two conductors which may be the two lead-in conductors for the antenna and wherein the control unit contains an indicator and receives impulses from the rotator unit to establish the correct follow-up indication.

Antenna rotators which have a remote control unit have previously been constructed; however, the present invention relates to a remote control rotator wherein only two wires need be used to interconnect the remote control unit and the rotator unit. Previously, at least three wires were required and often four or five wires in order to obtain a reversible rotational direction of the antenna rotator and to send some form of signal from the rotator unit down to the remote control unit so that the system would shut itself off upon re-establishing alignment. The present invention solves the problem of using only two conductors or wires for interconnecting the rotator unit and the remote control unit; and since only two conductors are needed, it is possible to utilize the two lead-in wires of the typical high frequency dipole antenna to convey the electrical requirements of the rotator unit and remote control unit. This may be accomplished by using high-pass filters to connect the radio device and the antenna to the lead-in wires and utilizing low-pass filters to connect the remote control unit and the rotator unit to the lead-in wires.

An object of the invention is to provide an impulsing indicator and remote control unit interconnected by only two wires to a reversible rotator unit.

Another object of the invention is to provide a remotely controlled rotator unit which is reversible in response to two different voltage conditions.

Another object of the invention is to provide an impulsing indicator and remote control unit which is operable by first and second current conditions to change the indicator position.

Another object of the invention is to provide low-pass and high-pass filters connected to antenna lead-in wires to separate the antenna high frequency currents from the control currents utilized between a remote control unit and a rotator unit.

Another object of the invention is to provide in a remotely controlled rotator unit a motor driven switch which provides different current conditions which control an impulsing indicator and which further control a switch energizing the rotator.

Still another object of the invention is to provide a reversible direction rotator unit controlled by a manually reversible selector means and indicator means in a remote control unit interconnected by only two conductors.

Still another object of the invention is to provide a voltage responsive electromagnetic means in a first unit controlled by a selector switch in a second unit to control the direction of rotation of a drive train in the first unit and with current responsive electromagnetic means in the sec-

2

ond unit controlled by an interrupter switch in the first unit to control the selector switch in the second unit.

Other objects and a fuller understanding of this invention may be had by referring to the following description and claims, taken in conjunction with the accompanying drawings, in which:

Figure 1 is a schematic diagram of the preferred embodiment of the invention;

Figure 2 is an end view of the rotator unit used in Figure 1;

Figure 3 is a sectional view on the line 3—3 of Figure 2;

Figure 4 is a sectional view on the line 4—4 of Figure 3;

Figure 5 is an enlarged view of a portion of Figure 4;

Figure 6 is a partial view on the line 6—6 of Figure 5; and

Figure 7 is a schematic diagram of a modified form of the invention.

The Figures 1 to 6 show the preferred form of the invention with Figure 1 schematically showing a remote control unit 11 and a rotator unit 12. The construction of the rotator unit 12 is shown in the Figures 2 to 6. The remote control unit 11 includes a transformer 13 having a primary 14 connectable to an alternating current source. The transformer 13 also has a center tapped secondary 15 having terminals 16, 17, and 18. Twelve volts are obtained between terminals 16 and 17, and twenty-four volts are obtained across the end terminals 16 and 18. A knob 19 is fastened to a shaft 20 and a detent wheel 21 is fastened to the shaft 20. A detent 22 holds the detent wheel 21 in any selected rotational position. An escapement wheel 25 is also journaled to the shaft 20 and is controlled by a rockable verge 26. The knob 19 carries a pointer 23 which co-operates with an indicator 24 moved in accordance with the movement of the escapement wheel 25. The verge 26 is pivoted at 27, and a spring 28 urges a tooth 29 of the verge 26 into engagement with the escapement wheel 25. When the verge 26 is rocked against the urging of the spring 28, a tooth 30 of the verge engages the escapement wheel 25 and thus permits step-by-step movement of this escapement wheel.

The detent wheel 21 carries a secondary selector switch 33 which is a double throw switch. The selector switch 33 includes first and second blades 34 and 35 insulatively carried on the detent wheel 21. These blades lie parallel to the shaft 20. A coil spring 36 has a first end 37 carried by a contact disk 39 and has a second end 38 carried by a second contact disk 40. The two contact disks 39 and 40 are electrically connected together and connected to a terminal 41. The escapement wheel 25 carries an insulator bar 42 which is parallel to the blades 34 and 35 and is wider than the width of the two blades. The blade 34 is adapted to make contact with a tongue 31 on the contact disk 40, and the blade 35 is adapted to make contact with a tongue 32 on the contact disk 39.

The position of the detent wheel 21 controls the position of a primary switch contact 44, and the position of the escapement wheel 25 controls the position of a primary switch contact 45. When the detent wheel 21 and escapement wheel 25 are aligned, the primary switch 44—45 is in an open condition, as caused by a cam 61 moved with wheel 25 and abuttable against switch contact 45. The primary switch 44—45 is connected in the energization leads to the primary 14.

The terminal 18 is connected to the blade 35 by a conductor 46, and the terminal 17 is connected to the blade 34 by a conductor 47. The terminal 41 is the common terminal of the selector switch 33, and it is connected to a winding 48 of a current relay 49. The other end of the winding 48 is connected by a conductor 50 to a terminal 51 of a low-pass filter 52. The other

input terminal 53 of the low-pass filter 52 is connected by a conductor 54 to the terminal 16. The low-pass filter 52 has output terminals 55 and 56 which are connected to lead-in wires 57 and 58. A high-pass filter 59 connects a radio device 60 to the lead-in wires 57 and 58.

The upper end of the lead-in wires 57 and 58 is connected through a second low-pass filter 68 to the rotator unit 12. The two lead-in wires are connected to an antenna 69 through a second high-pass filter 70. A voltage solenoid 71 is connected across the output terminals 72 and 73 of the low-pass filter 68. The voltage solenoid 71 has a movable core 74 and also controls a switch blade 75. The switch blade 75 co-operates with switch contacts 76 and 77. The switch contact 77 is connected through a choke 78 to a terminal 79 to which this switch contact 76 is connected. The motor in the rotator unit 12 is a single phase shaded pole induction motor 80 having one terminal connected to the terminal 79. The other terminal of the motor 80 is connected through an interrupter switch 81 to the terminal 72 of the filter 68. The motor 80 drives a speed reducing gear train 84 which has an output 85 connected to the shaft 86 of the antenna 69. The interrupter switch 81 is actuated by the gear train 84 and is designed to be only momentarily actuated to an open condition and cannot be maintained in an open position.

The Figures 2 to 6 show the details of construction of the gear train 84. The rotator unit 12 includes a housing 89 which encloses the motor 80. The motor 80 has a drive shaft 90 carrying a drive pinion 91. The drive pinion 91 meshes with an idler pinion 92 and with a first drive gear 93. The idler pinion 92 meshes with a second drive gear 94. The Figure 5 shows to an enlarged scale that the drive gears 93 and 94 are coaxial and mounted on hubs 95 and 96, respectively, which are journaled on an intermediate shaft 97. Because of the idler pinion 92, the drive gears 93 and 94 rotate in opposite directions. The intermediate shaft 97 is axially connected to the solenoid core 74 as shown in Figure 1. Thus, the intermediate shaft 97 may axially move to the right from a first limit position as shown in Figure 5 to a second limit position. The shaft 97 carried pins 98 and 99 with the pin 98 receivable in a recess 100 in the hub 95 and engageable with a drive lug 102 on the inner periphery of this recess 100. Similarly, the pin 99 is receivable in a recess 101 in the hub 96 and engageable with a drive lug 103 in this recess 101. The recesses 100 and 101 are oppositely disposed; and hence, the pins 98 and 99 are alternately engageable with the drive lugs 102 and 103. These pins and lugs thus form a positive clutch with the intermediate shaft 97 being drivingly connected to the drive gear 94 in the position shown in Figure 5. Alternately, upon movement of the intermediate shaft to the right to the second limit position, the second drive gear 94 is disengaged from the shaft 97 and the second drive gear 93 is placed in driving connection with the shaft 97. The pull of the solenoid 71 is to the right as viewed in Figure 5, and the gear train 84 may be disposed so that gravity will urge the shaft 97 to the left to the first limit position or a spring means may be utilized for this urging. The intermediate shaft 97 drives a pinion 104 which connects through additional gearing 105 to drive a shaft mount 106. A cam disk 107 is driven from the drive train 84 to momentarily actuate the interrupter switch 81 to an open condition.

Operation

The rotator unit 12 is a reversible unit which will rotate the antenna shaft 86 in either rotational direction and in so doing will momentarily open the interrupter switch 81. The remote control unit 11 controls the operation of the rotator unit 12 and further contains an indicator 24. The operator will grasp the knob 19 to rotate it in either

direction. If it is rotated clockwise, for example, the shaft 20, the detent wheel 21, and the pointer 23 all move clockwise. The escapement wheel 25 remains stationary since it is held by the tongue 29 of the verge 26. Thus, the insulator bar 42 remains stationary, and the primary switch 44-45 closes because of the non-alignment of the detent wheel 21 and escapement wheel 25. This energizes the transformer 13. The blade 34 electrically contacts the tongue 31 on the contact disk 40. This completes the circuit of the secondary 15 from the terminal 17 through the conductor 47, the blade 34, contact disk 40, terminal 41, current relay 49, conductor 50, to the terminal 51 of the filter 52. The terminal 16 of the secondary is connected by conductor 54 to the terminal 53 of the filter 52. This places twelve volts across terminals 51 and 53. These twelve volts are passed by the low-pass filter 52 through the lead-in wires and low-pass filter 68 to the rotator unit 12.

The voltage solenoid 71 is voltage responsive and has insufficient pull on twelve volts to move the core 74 into the solenoid 71. Thus, the shaft 97 is in the position shown in Figure 5 for a drive connection through drive gear 94. This will rotate the antenna shaft 86 in the appropriate direction. As the shaft 86 rotates, the interrupter switch 81 is momentarily actuated by the cam disk 107. This momentarily opens the series circuit of the switch 81 and motor 80. During this momentary interruption the load on the secondary 15 will be considerably reduced since only the voltage solenoid 71 is being energized in the rotator unit 12 rather than the solenoid 71 plus the motor 80. This causes a considerable current change, and the current relay 49 in the remote control unit 11 is responsive to this change in current. Upon initial energization of the motor 80, the current relay 49 would be energized to rock the verge 26 causing tongue 30 to be in engagement with the escapement wheel 25. During the momentary interruptions caused by the interrupter switch 81 the current relay 49 will drop out to rock the verge 26. This will cause a step-by-step arcuate movement of the escapement wheel 25 for each interruption by the interrupter switch 81. This will continue until the indicator 24 again becomes aligned with the pointer 23 whereupon the primary switch 44-45 will be opened.

The knob 19 may be rotated in a counterclockwise direction which means that the transformer 13 will again become energized, the blade 35 will electrically contact the tongue 32 of the contact disk 39 to place twenty-four volts across the terminals 51 and 53. With this higher voltage, the voltage solenoid 71 will be energized sufficiently to move the core 74 into the solenoid 71, and hence, clutch 99-103 will be disengaged and clutch 98-102 will become engaged. This will rotate the antenna shaft in a direction opposite to that formerly effected. The cam disk 107 will again periodically actuate the interrupter switch 81 to control the current relay 49. The actuation of the voltage solenoid 71 will close switch blade 75 against contact 77 which will place in series with the motor 80, the choke 78. This makes more nearly constant the current supplied to the motor 80 and to the current relay 49.

Details of construction of the remote control unit 11 and rotator unit 12 may be similar to that shown in the copending Application Serial No. 190,506, filed October 17, 1950, entitled "Remote Control Impulsing Rotator," now Patent No. 2,682,628, issued June 29, 1954.

The Figure 7 shows another modification of the invention. A remote control unit 115 contains many parts similar to those shown in the remote control unit 11, and hence, is marked with the same reference numbers. The blade 34 is connected by a conductor 116 through a dry disk rectifier 118 to a terminal 120. The blade 35 is connected by a conductor 117 through a dry disk rectifier 119 to the terminal 120. The rectifiers 118 and 119

are connected in opposition relative to the terminal 120. A conductor 121 interconnects the terminal 120 and a terminal 122 on a solenoid 123. The solenoid 123 has first and second windings 124 and 125. The winding 124 has a second terminal 126, and the winding 125 has a second terminal 127. The terminal 126 is connected by a conductor 128 to a terminal 129 of a secondary 130 of a transformer 131. A terminal 132 of the secondary 130 is connected by a conductor 133 to the terminal 41. The conductor 128 connects to the low-pass filter 52, and a conductor 134 connects the terminal 127 to the low-pass filter 52. The lead-in wires 57 and 58 are again connected to a second low-pass filter 68 having terminals 72 and 73. A direct current permanent magnet motor 138 is connected in series with the interrupter switch 81 across the terminals 72 and 73. The motor 138 drives the antenna shaft 86 through a drive train 139 which includes the cam disk 107 actuated by the interrupter switch 81.

Operation

The circuit of Figure 7 again uses an impulsing indicator and a control unit 115 to control a rotator unit 114. When the operator turns the knob 19 clockwise, the transformer 131 will become energized and the blade 34 will conduct current through the rectifier 118, through the winding 125, to the low-pass filter 52. This will supply direct current of one polarity to the direct current motor 138 causing it to rotate in a particular direction. The current flow through the direct current motor 138 plus the permanent magnet in this motor is a combined electrical and magnetic means which determines the direction of rotation. The speed reducing drive train 139 will thus rotate the antenna shaft 86 in the appropriate direction. The cam disk 107 will momentarily actuate the interrupter switch to an open condition. This will de-energize the solenoid winding 125. The solenoid winding 124 remains energized continuously from the secondary 130 through conductors 133 and 128 and the selected one of the rectifiers 118 and 119. The windings 124 and 125 are wound in opposition and of equal ampere turns so that upon de-energization of the winding 125 by the opening of the interrupter switch 81, the solenoid 123 will exert a pull to rock the verge 26. When the interrupter switch 81 again closes after its momentary open condition, the solenoid 123 will be effectively neutralized by equal and opposite energization on the windings 124 and 125. This releases the verge 126 under the urging of the spring 28. The escapement wheel 25 will thus step-by-step angularly move to a position coinciding with the selected position of the knob 19 and pointer 23. The mechanism will shut itself off upon re-alignment of the pointer 23 and indicator 24.

A counterclockwise rotation of the knob 19 will cause the blade 35 to make contact with the tongue 32; and hence, current will flow through the rectifier 119. Each of the windings 124 and 125 will thus have current flow therethrough in a direction opposite to that which was formerly effected. However, these two windings are still equally and oppositely energized so that there is no pull on the verge 26. The opposite polarity of direct current, combined with the magnetic field of the permanent magnet, will cause the direct current motor 138 to rotate in the opposite direction and hence rotate the antenna shaft 86 in the opposite direction. Again, the momentary actuation of the interrupter switch 81 will periodically de-energize the solenoid winding 125 to rock the verge 26, and hence, permit re-alignment of the pointer 23 and indicator 24 to de-energize the remote control unit 115 as well as the rotator unit 114.

In Figures 1 and 7 it may be noted that there is a voltage responsive electromagnetic means in the rotator unit controlled by a selector switch in the control unit to control the direction of rotation and further that there is a current responsive electromagnetic means in the

control unit controlled by the interrupter switch in the rotator unit to control the selector switch in the control unit.

The requirement of only two conductors interconnecting the rotator and control units makes possible the utilization of the lead-in wires 57 and 58 as the current carrying conductors for the power to the rotator unit as well as the signals sent back from the rotator unit to control the selector switch in the control unit. Further, 10 these two conductors carry power current which has two different voltage conditions so that a voltage responsive electromagnetic means in the rotator unit may determine the correct direction of rotation of the antenna shaft.

The power current and control signals on the two conductors 57 and 58 is of power frequency, such as sixty cycle, or is direct current which in either event will be passed by the low-pass filters 52 and 68 which have low impedance to low frequency and high impedance to high frequency. Further, the radio signals, such as H. F., 20 V. H. F., or U. H. F., are passed from the antenna 69 through the high-pass filters 70 and 59 to the radio device 60. These high-pass filters will have high impedance to low frequency and direct current and low impedance to high frequency. 25 Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A mechanism comprising a control unit and a drive unit interconnectable by two conductors, said drive unit including an electric motor connectable to said two conductors and driving a drive train, a motor driven interrupter switch connectable to said two conductors and actuatable to establish first and second current conditions on said two conductors, and first electromagnetic means responsive to first and second voltage conditions to determine the rotational direction of said drive train, said control unit including voltage terminals, a selector switch connected to said terminals and to said two conductors to select said first and second voltage conditions on said two conductors, and second electromagnetic means connected to said two conductors and responsive to said first and second current conditions on said two conductors and connected to operate said selector switch.
2. A remotely controlled antenna rotator comprising a remote control unit and an antenna rotator unit for rotating an antenna having first and second lead-in wires connectable to a radio device, said antenna rotator unit including, a housing, an antenna shaft mount rotatable relative to said housing, a drive train having an output connected to said shaft mount, a low-pass filter, an electric motor connectable through said low-pass filter to said lead-in wires and driving said drive train, a motor driven interrupter switch connectable to said lead-in wires and actuatable to establish first and second current conditions on said lead-in wires, first electromagnetic means responsive to first and second voltage conditions to determine the rotational direction of said drive train, and a high pass filter to connect said antenna to said lead-in wires, said remote control unit including voltage terminals, a selector switch connected to said terminals and through a second low-pass filter to said lead-in wires to select said first and second voltage conditions, and second electromagnetic means connected to said lead-in wires and responsive to said first and second current conditions, and means to operate said selector switch from said second electromagnetic means.
3. A remotely controlled antenna rotator comprising a remote control and indicator unit and an antenna rotator unit for rotating an antenna having first and sec-

ond lead-in wires connectable to a radio device, said antenna rotator unit including a housing, an antenna shaft mount rotatable relative to said housing, a drive train having an output connected to said shaft mount, a low-pass filter, an electric motor connectable through said low-pass filter to said lead-in wires and driving said drive train, a motor driven interrupter switch connectable to said lead-in wires and actuatable to establish first and second current conditions on said lead-in wires, first electromagnetic means responsive to first and second voltage conditions to determine the rotational direction of said drive train, and a high-pass filter to connect said antenna to said lead-in wires, said remote control unit including voltage terminals, a selector switch connected to said terminals and through a second low-pass filter to said lead-in wires to select said first and second voltage conditions, and second electromagnetic means connected to said lead-in wires and responsive to said first and second current conditions, an indicator operated with said selector switch, and means to operate said indicator and said selector switch from said second electromagnetic means.

4. A mechanism comprising a control unit and a drive unit interconnectable by only first and second conductors, said drive unit including a housing, a drive train in said housing having an output and an input, a two terminal electric motor, means for connecting said electric motor to said drive train input to drive said output thereof in either direction, an interrupter switch in said housing, means driven in accordance with the drive of said drive train to actuate said interrupter switch, means for connecting said first and second conductors to said two motor terminals and to said interrupter switch to provide energization to said motor, said control unit including, a frame, a reversibly movable escapement device in said frame, means to selectively urge said escapement device in opposite directions, a selector switch physically connected for operation with said selective means, voltage terminals, a verge carried by said frame and operable to release said escapement device in either direction, first electromagnetic means in said frame operable to operate said verge means for connecting said manual selector switch and said voltage terminals to said two conductors to select first and second voltage conditions on said two conductors corresponding to the two movement directions of said escapement device, said mechanism also including second electromagnetic means for establishing first and second movement directions of said drive train output in accordance with the selected one of said first and second voltage conditions on said two conductors, actuation of said interrupting switch effecting first and second current conditions on said two conductors, and said first electromagnetic means being responsive to said first and second current conditions on said two conductors to operate said verge to release said escapement device.

5. A mechanism comprising a remote control unit and a rotator unit interconnectable by only first and second conductors, said rotator unit including, a drive train having an output and an input, a two terminal electric motor, means for connecting said electric motor to said drive train input to rotate said output in either direction, a normally closed interrupter switch in said housing, means driven in accordance with either rotational direction of said drive train output to repetitively and only momentarily actuate said interrupter switch to an open condition, means for connecting said first and second conductors to said two motor terminals through said interrupter switch, said remote control unit including, a frame, a reversibly rotatable escapement device journaled in said frame, spring means, manual means to selectively stress said spring means in opposite directions to urge said escapement device in opposite rotational directions, a manual double-throw selector switch physically connected for simultaneous operation with said manual means, alternating current terminals, a rockable verge carried by said frame and operable to release said escapement device in either direction step by step, first electromagnetic means in said frame operable to operate said verge, means for connecting said manual selector switch and said alternating current terminals in series to said two conductors to select first and second voltage conditions corresponding to the two rotational directions of said escapement device, said mechanism also including second electromagnetic means for establishing first and second rotational directions of said mount in accordance with the selected one of said first and second voltage conditions, either direction of operation of said mount effecting periodic and momentary operation of said interrupting switch to said open condition, open and closed conditions of said interrupting switch effecting first and second current conditions on said conductors, and said first electromagnetic means being responsive to said first and second current conditions to rock said verge to release said escapement device.

6. A mechanism comprising a remote control unit and a rotator unit interconnectable by first and second conductors, said rotator unit including a housing, a mount rotatable relative to said housing, a reversible direction speed reducing drive train having an output connected to said mount and having an input, an electric motor having two terminals, means for connecting said electric motor to said drive train input to rotate said mount in either direction, a normally closed interrupter switch in said housing, means driven in accordance with either rotational direction of said mount to repetitively and only momentarily actuate said interrupter switch to an open condition, means for connecting said first and second conductors to said two motor terminals through said interrupter switch, said remote control unit including, a frame, a reversibly rotatable escapement device journaled in said frame, spring means, manual means to selectively stress said spring means in opposite directions to urge said escapement device in opposite rotational directions, a manual double-throw selector switch physically connected for simultaneous operation with said manual means, alternating current terminals, a rockable verge carried by said frame and operable to release said escapement device in either direction, a normally closed interrupter switch in said housing, means driven in accordance with either rotational direction of said mount to repetitively and only momentarily actuate said interrupter switch to an open condition, means for connecting said first and second voltage conditions, either direction of operation of said drive train output effecting periodic and momentary operation of said interrupting switch to said open condition, open and closed conditions of said interrupting switch effecting first and second current conditions on said conductors, and said first electromagnetic means being responsive to said first and second current conditions to operate said verge to release said escapement device.

7. A mechanism comprising a remote control unit and a rotator unit interconnected by first and second conductors, said rotator unit including a housing, a mount rotatable relative to said housing, a reversible direction speed reducing drive train having an output connected to said mount and having an input, an electric motor having two terminals, means for connecting said electric motor to said drive train input to rotate said mount in either direction, a normally closed interrupter switch in said housing, means driven in accordance with either rotational direction of said mount to repetitively and only momentarily actuate said interrupter switch to an open condition, means for connecting said first and second conductors to said two motor terminals through said interrupter switch, said remote control unit including, a frame, a reversibly rotatable escapement device journaled in said frame, spring means, manual means to selectively stress said spring means in opposite directions to urge said escapement device in opposite rotational directions, a manual double-throw selector switch physically connected for simultaneous operation with said manual means, alternating current terminals, a rockable verge carried by said frame and operable to release said escapement device in either direction, a normally closed interrupter switch in said housing, means driven in accordance with either rotational direction of said mount to repetitively and only momentarily actuate said interrupter switch to an open condition, means for connecting said first and second voltage conditions, either direction of operation of said mount effecting periodic and momentary operation of said interrupting switch to said open condition, open and closed conditions of said interrupting switch effecting first and second current conditions on said conductors, and said first electromagnetic means being responsive to said first and second current conditions to rock said verge to release said escapement device.

8. A mechanism comprising a remote control unit and a rotator unit interconnected by first and second conductors, said rotator unit including a housing, a mount rotatable relative to said housing, a reversible direction speed reducing drive train having an output connected to said mount and having an input, an electric motor having two terminals, means for connecting said electric motor to said drive train input to rotate said mount in either direction, a normally closed interrupter switch in said housing, means driven in accordance with either rotational direction of said mount to repetitively and only momentarily actuate said interrupter switch to an open condition, means for connecting said first and second voltage conditions, either direction of operation of said drive train output effecting periodic and momentary operation of said interrupting switch to said open condition, open and closed conditions of said interrupting switch effecting first and second current conditions on said conductors, and said first electromagnetic means being responsive to said first and second current conditions to operate said verge to release said escapement device.

conductors to said two motor terminals through said interrupter switch, said remote control unit including, a frame, a reversibly rotatable ratcheting device journaled in said frame, spring means, manual means to selectively stress said spring means in opposite directions to urge said ratcheting device in opposite rotational directions, a manual double-throw selector switch physically connected for simultaneous operation with said manual means, a step-down transformer having a primary adapted for energization from an alternating current source and having a secondary, a rockable verge carried by said frame and operable to release said ratcheting device in either direction step-by-step, first electromagnetic means in said frame operable to operate said verge, means for connecting said manual selector switch and said transformer secondary in series to said two conductors to select first and second voltage conditions corresponding to the two rotational directions of said ratcheting device, said mechanism also including second electromagnetic means for establishing first and second rotational directions of said mount in accordance with the selected one of said first and second voltage conditions, either direction of operation of said mount effecting periodic and momentary operation of said interrupting switch to said open condition, open and closed conditions of said interrupting switch effecting first and second current conditions on said conductors, and said first electromagnetic means being responsive to said first and second current conditions to rock said verge to release said ratcheting device.

8. A remotely controlled rotator comprising an impulsing indicator and remote control unit and a rotator unit interconnectable by only first and second conductors, said rotator unit including, a housing, a mount rotatable relative to said housing, a reversible direction speed reducing drive train having an output connected to said mount and having an input, a two terminal electric motor, means for connecting said electric motor to said drive train input to rotate said mount in either direction, a normally closed interrupter switch in said housing, means driven in accordance with either rotational direction of said mount to repetitively and only momentarily actuate said interrupter switch to an open condition, first and second terminals insulatively carried on said housing, means for connecting said first and second housing terminals to said two motor terminals through said interrupter switch, said first and second housing terminals adapted to be connected to said high frequency antenna, and said first and second housing terminals adapted to be connected to said antenna lead-in wires, said remote control unit including, a frame, a reversibly rotatable ratcheting device journaled in said frame, spring means, manual means to selectively stress said spring means in opposite directions to urge said ratcheting device in opposite rotational directions, selector means operable in correspondence with said manual means to select the degree of rotation and hence the ultimate position of said mount relative to said frame, a manual double throw selector switch physically connected for simultaneous operation with said manual means, a step-down transformer having a primary adapted for energization from an alternating current source and having a secondary, a rockable verge carried by said frame and operable to release said ratcheting device in either direction step by step, first electromagnetic means in said frame operable to rock said verge, first and second frame terminals insulatively carried by said frame, means to connect said two conductors to said frame terminals, means for connecting said manual selector switch and said transformer secondary in series with said frame terminals to select first and second voltage conditions corresponding to the two rotational directions of said ratcheting device, said remotely controlled rotator also including second electromagnetic means for establishing first and second rotational directions of said mount in accordance with the selected one of said first and second voltage conditions, either direction of opera-

tion of said mount effecting periodic and momentary operation of said interrupting switch to said open condition, open and closed conditions of said interrupting switch effecting first and second current conditions on said conductors, a position indicator operable in correspondence with movement of said ratcheting device, and said first electromagnetic means being responsive to said first and second current conditions to rock said verge to release said ratcheting device and thereby step-by-step move said indicator into a position corresponding to the position of said selector means.

9. An impulsing indicator remotely controlled antenna rotator comprising a remote control and indicator unit and an antenna rotator unit for rotating a high frequency antenna having a shaft and having first and second lead-in wires connectable to a radio device, said antenna rotator unit including, a housing, an antenna shaft mount rotatable relative to said housing, a reversible direction speed reducing drive train having an output connected to said shaft mount and having an input, a two terminal electric motor, means for connecting said electric motor to said drive train input to rotate said shaft mount in either direction, a normally closed interrupter switch in said housing, means driven in accordance with either rotational direction of said shaft mount to repetitively and only momentarily actuate said interrupter switch to an open condition, first and second terminals insulatively carried on said housing, means for connecting said first and second housing terminals to said two motor terminals through said interrupter switch, said first and second housing terminals adapted to be connected to said high frequency antenna, and said first and second housing terminals adapted to be connected to said antenna lead-in wires, said remote control unit including, a frame, a reversibly rotatable ratcheting device journaled in said frame, spring means, manual means to selectively stress said spring means in opposite directions to urge said ratcheting device in opposite rotational directions, selector means operable in correspondence with said manual means to select the degree of rotation and hence the ultimate position of said antenna shaft, a manual double throw selector switch physically connected for simultaneous operation with said manual means, a step-down transformer having a primary adapted for energization from an alternating current source and having a secondary, a rockable verge carried by said frame and operable to release said ratcheting device in either direction step by step, first electromagnetic means in said frame operable to rock said verge, first and second frame terminals insulatively carried by said frame, means to connect said lead-in wires to said first and second frame terminals, said radio device adapted to be connected to said lead-in wires near said remote control unit, means for connecting said manual selector switch and said transformer secondary in series with said frame terminals to select first and second voltage conditions corresponding to the two rotational directions of said ratcheting device, said antenna rotator also including second electromagnetic means for establishing first and second rotational directions of said shaft mount in accordance with the selected one of said first and second voltage conditions, either direction of rotation of said shaft mount effecting periodic and momentary operation of said interrupting switch to said open condition, open and closed conditions of said interrupting switch effecting first and second current conditions on said lead-in wires, an antenna position indicator operable in correspondence with movement of said ratcheting device, and said first electromagnetic means being responsive to said first and second current conditions to rock said verge to release said ratcheting device and thereby step-by-step move said indicator into a position corresponding to the position of said selector means.

10. An impulsing indicator remotely controlled antenna rotator comprising a remote control unit and an antenna

rotator unit for rotating a high frequency antenna having first and second lead-in wires connectable to a radio device, said antenna rotator unit including, a housing, an antenna shaft mount rotatable relative to said housing, a reversible direction speed reducing drive train having an output connected to said shaft mount and having an input, a two terminal electric motor, means for connecting said electric motor to said drive train input, electromagnetic means in said housing responsive to first and second voltage conditions to selectively rotate said shaft mount in either direction, a normally closed interrupter switch in said housing, means driven in accordance with either rotational direction of said shaft mount to repetitively and only momentarily actuate said interrupter switch to an open condition, first, second, third, and fourth terminals insulatively carried on said housing, four terminal low-pass filter means connecting said first and second housing terminals to said two motor terminals through said interrupter switch, said low-pass filter means having a high impedance to high frequency, high-pass filter means having a high impedance to low frequency connecting said first and second housing terminals with said third and fourth housing terminals, said third and fourth housing terminals adapted to be connected to said high frequency antenna, and said first and second housing terminals adapted to be connected to said antenna lead-in wires, said remote control unit including, a frame, a reversibly rotatable ratcheting device journaled in said frame, spring means, manual means to selectively stress said spring means in opposite directions to urge said ratcheting device in opposite rotational directions, selector means operable in correspondence with said manual means to select the degree of rotation and hence the ultimate position of said antenna shaft, a manual double throw selector switch physically connected for simultaneous operation with said manual means, a step-down transformer having a primary adapted for energization from an alternating current source and having a secondary, a rockable verge carried by said frame and operable to release said ratcheting device in either direction step by step, first and second frame terminals insulatively carried by said frame, second four terminal low-pass filter means connected to said lead-in wires at said remote control unit, said second low-pass filter means having a high impedance to high frequency, said radio device adapted to be connected to said lead-in wires on the antenna side of said second low-pass filter means through a second high-pass filter means having a high impedance to low frequency, second electromagnetic means in said frame operable to rock said verge, means for connecting said manual selector switch and said transformer secondary in series with said second low-pass filter means to select said first and second voltage conditions corresponding to the two rotational directions of said ratcheting device, either direction of rotation of said shaft mount effecting periodic and momentary operation of said interrupting switch to said open condition, open and closed conditions of said interrupting switch effecting first and second current conditions on said lead-in wires, an antenna position indicator operable in correspondence with movement of said ratcheting device, and said second electromagnetic means being responsive to said first and second current conditions to rock said verge to release said ratcheting device and thereby step-by-step move said indicator into a position corresponding to the position of said selector means.

11. A remotely controllable rotator interconnectable by only first and second conductors, comprising a rotator unit and a remote control unit, said rotator unit including a housing, an alternating current single phase motor in said housing, a mount in said housing rotatable relative thereto, a drive train interconnecting said motor and said mount, first and second drive gears in said drive train rotatable in opposite rotational directions, positive clutch means in said drive train alternately engageable with a

selected one of said first and second drive gears by movement from one limit position to another, a voltage responsive solenoid connected to and capable of moving said clutch means from one limit position to the other by an applied voltage of a first given value, yet incapable of moving said clutch means from said one limit position to the other by an applied voltage of only a second given value, a normally closed interrupter switch in said housing, means driven in accordance with the rotation of said mount to repetitively and only momentarily actuate said interrupter switch to an open condition, means for connecting said motor and said interrupter switch in series to said first and second conductors, means for connecting said solenoid to said conductors in parallel with said motor and switch series combination, said remote control unit including, a frame, a reversibly rotatable escapement device journaled in said frame, spring means, manual means to selectively stress said spring means in opposite directions to urge said escapement device in opposite rotational directions, a double-throw selector switch and connected for simultaneous operation with said manual means, first, second, and third terminals adapted to be energized by an alternating current source with said first given voltage between said first and third terminals and said second given voltage between said first and second terminals, a rockable verge carried by said frame and operable to permit step by step rotational movements of said escapement device in either rotational direction, a current responsive relay connected to rock said verge, means for connecting said selector switch to said alternating current source terminals and in series with said current relay and with said two conductors, said current relay energizable to actuated condition by current flow therethrough to both said motor and said voltage responsive solenoid and incapable of energization to actuated condition by current flow therethrough to only said voltage responsive solenoid.

12. A remotely controllable antenna rotator for a high frequency antenna having first and second lead-in wires connectable to a radio device, comprising an antenna rotator unit and a remote control unit, said antenna rotator unit including a housing, a shaded pole alternating current single phase motor in said housing, an antenna mount in said housing rotatable relative thereto, a drive pinion driven by said motor, first and second drive gears coaxially journaled on a rotatable and longitudinally movable drive shaft, an idler pinion in mesh with said drive pinion and said second drive gear, said first drive gear being in mesh with said drive pinion to thereby establish opposite rotational directions of said coaxial drive gears, first and second positive clutches coaxial with said drive shaft and alternately engageable between said drive shaft and a selected one of said first and second drive gears by longitudinal movement from a first limit position to a second, said clutches being urged into said first limit position, a gear train inter-connecting said drive shaft and said antenna mount, a voltage responsive solenoid embracing an end of said drive shaft as the armature thereof and capable of longitudinally moving said drive shaft from said first limit position to said second limit position by a first given applied voltage, yet incapable of longitudinally moving said drive shaft from said first limit position to said second limit position by a second given applied voltage of a smaller magnitude, a normally closed interrupter switch in said housing, means driven in accordance with the rotation of said antenna mount to repetitively and only momentarily actuate said interrupter switch to an open condition, a first high-pass filter to connect said antenna to said lead-in wires, a first low-pass filter connected to said lead-in wires at said antenna rotator unit, means for connecting said motor and said interrupter switch in series to said first low-pass filter, means for connecting said solenoid to said first low-pass filter in parallel with said motor and switch series combination, said remote control unit including, a

frame, a reversibly rotatable ratcheting device journaled in said frame, spring means, manual means to selectively stress said spring means to urge said ratcheting device in opposite rotational directions, a double-throw selector switch having first and second contacts and a common contact and connected for simultaneous operation with said manual means, first, second, and third terminals adapted to be energized by an alternating current source with said second given voltage between said first and second terminals and said first given voltage between said first and third terminals, means for connecting said first and second selector switch contacts to said second and third source terminals, respectively, a rockable verge carried by said frame and operable to permit step by step rotational movements of said ratcheting device in either rotational direction, a second low-pass filter connected to said lead-in wires at said remote control unit, a second high-pass filter to connect said radio device to said lead-in wires, means for connecting said first source terminal to said second low-pass filter, a current responsive relay connected to rock said verge, means for connecting said selector switch common contact through said current relay to said second low-pass filter, said current relay energizable to actuated condition by current flow therethrough to both said motor and said voltage responsive solenoid and incapable of energization to actuated condition by current flow therethrough to only said voltage responsive solenoid.

13. A remotely controlled rotator comprising an impulsive indicator and remote control unit and a rotator unit interconnectable by first and second conductors, said rotator unit including a housing, a mount rotatable relative to said housing, a reversible direct current permanent magnet motor interconnecting said housing and said mount to rotate said mount in selective directions, first and second electrical terminals on said motor for energizing same, a normally closed interrupter switch in said housing capable of being only momentarily actuated to an open condition, means driven in accordance with the rotation of said mount to repetitively actuate said switch, first and second terminals insulatively carried on said housing, means for connecting said first and second housing terminals to said first and second motor terminals through said interrupter switch, said first and second housing terminals adapted to be connected to said conductors, said impulsive indicator and remote control unit including a frame, a reversibly rotatable ratcheting device carried in said frame, spring means selectively stressable to urge said ratcheting device in opposite rotational directions, selector means operable in correspondence with said spring means to select the degree of rotation and hence the ultimate position of said mount relative to said frame, a rockable verge to release said ratcheting device in either direction step by step, a solenoid having an armature connected to rock said verge, first and second source terminals adapted to be energized by an alternating current source, a double-throw selector switch having a common connection connected to said first source terminal, means physically interconnecting said selector switch and said spring means for simultaneous actuation, first and second rectifiers, winding means on said solenoid, said winding means having a terminal, means for connecting said rectifiers in opposition to said winding means terminal and to said double-throw contacts of said selector switch, means for connecting said winding means to said second source terminal and to said lead-in wires, either direction of rotation of said mount effecting periodic and only momentary operation of said interrupting switch to said open condition, open and closed conditions of said interrupting switch effecting off and on current conditions on said conductors, a position indicator operable in correspondence with movement of said ratcheting device, and said solenoid being responsive to said off and on current conditions on said conductors and on said winding means to rock said verge

to release said ratcheting device and thereby move said indicator step by step into a position corresponding to the position of said ratcheting device.

14. An impulsing indicator remotely controlled antenna rotator comprising a remote control unit and an antenna rotator unit for rotating a high frequency antenna having a shaft and having first and second lead-in wires connectable to a radio device, said antenna rotator unit including a housing, an antenna shaft mount rotatable relative to said housing to rotate said antenna shaft, a reversible direct current permanent magnet motor interconnecting said housing and said mount to rotate said mount in selective directions, first and second electrical terminals on said motor for energizing same, a normally closed interrupter switch in said housing capable of being only momentarily actuated to an open condition, means driven in accordance with the rotation of said antenna mount to repetitively actuate said switch, first, second, third, and fourth terminals insulatively carried on said housing, four terminal low-pass filter means connecting said first and second housing terminals to said first and second motor terminals through said interrupter switch, said low-pass filter means having a high impedance to high frequency, high-pass filter means having a high impedance to direct current connecting said first and second housing terminals with said third and fourth housing terminals, said third and fourth housing terminals adapted to be connected to said high frequency antenna, and said first and second housing terminals adapted to be connected to said antenna lead-in wires, said remote control unit including a frame, a reversibly rotatable ratcheting device carried in said frame, spring means selectively stressable to urge said ratcheting device in opposite rotational directions, a rockable verge to release said ratcheting device in either direction step by step, a solenoid having an armature connected to rock said verge, first and second source terminals adapted to be energized by an alternating current source, a double-throw selector switch having a common connection connected to said first source terminal, means physically interconnecting said selector switch and said spring means for simultaneous actuation, first and second rectifiers, winding means on said solenoid, said winding means having a terminal, means for connecting said rectifiers in opposition to said winding means terminal and to said double-throw contacts of said selector switch, a second four terminal low-pass filter means, means for connecting said winding means to said source terminals and to two terminals of said second low-pass filter means, means for connecting the remaining two terminals of said second low-pass filter means to said lead-in wires, said second low-pass filter means having a low impedance to direct current and a high impedance to high frequency, and said radio device adapted to be connected to said lead-in wires on the antenna side of said second low-pass filter means through a second high-pass filter means having a low impedance to high frequency and a high impedance to direct current, either direction of rotation of said mount effecting periodic and only momentary operation of said interrupting switch to said open condition, open and closed conditions of said interrupting switch effecting off and on current conditions on said lead-in wires, an antenna position indicator operable in correspondence with movement of said ratcheting device, and said solenoid being responsive to said off and on current conditions on said lead-in wires and on said winding means to rock said verge to release said ratcheting device and thereby move said indicator step by step into a position corresponding to the position of said ratcheting device.

15. A remotely controlled antenna rotator comprising a remote control unit and an antenna rotator unit interconnectable by two conductors, said antenna rotator unit including, a housing, an antenna shaft mount rotatable relative to said housing, a drive train having an output connected to said shaft mount, an electric motor driving said drive train, means for connecting said motor to said

two conductors, a motor driven interrupter switch connectable to said two conductors and actuatable to establish first and second current conditions on said two conductors, first electromagnetic means responsive to first and second voltage conditions to determine the rotational direction of said drive train, said remote control unit including voltage terminals, a selector switch connected to said terminals and to said two conductors to select said first and second voltage conditions on said two conductors, second electromagnetic means connected to said two conductors and responsive to said first and second current conditions on said two conductors, and means to operate said selector switch from said second electromagnetic means.

16. A control and power system operable from a first type power voltage source and comprising, control and power units interconnectable by only first and second conductors, energization means for supplying said first type power voltages from said control unit to said two conductors and hence to said power unit for use therein, electrical control means for supplying control voltage conditions on said two conductors from said control unit to said power unit for control thereof, and second electrical control means for supplying control current conditions on said two conductors from said power unit to said control unit for control thereof.

17. A control and power system operable from a first type power voltage source and comprising, control and power units interconnectable by only first and second conductors, means for supplying said first type power voltages from said control unit to said two conductors and hence to said power unit for use therein, means for conducting second type voltages on said two conductors from a point near said power unit to a point near said control unit, means for supplying control voltage conditions on said two conductors from said control unit to said power unit for control thereof, means for supplying control current conditions on said two conductors from said power unit to said control unit for control thereof, and means in said control unit for additionally utilizing said control current conditions as indicating means.

18. A power and control system comprising; a control unit and a drive unit interconnectable by two conductors;

said drive unit including, an electric motor connectable to said two conductors, a drive train driven by said motor, first electrical means driven by said motor to establish first and second current conditions on said two conductors, and first electromagnetic means responsive to first and second voltage conditions on said two conductors to determine first and second conditions of said drive train; said control unit including voltage terminals, second electrical means connected to said terminals and to said two conductors to select said first and second voltage conditions thereon, and second electromagnetic means connected to said two conductors and responsive to said first and second current conditions on said two conductors and connected to operate said second electrical means.

15 19. A power and control system comprising; a control unit and a drive unit interconnectable by only two conductors; said drive unit including, an electric motor connectable only to said two conductors, a drive train driven by said motor, first electrical means driven by said motor to establish first and second current conditions on said two conductors, and first electromagnetic means responsive to first and second voltage conditions on only said two conductors to determine the rotational direction of said drive train; said control unit including voltage terminals, second electrical means connected to said terminals and to said two conductors to select said first and second voltage conditions thereon, second electromagnetic means connected to said two conductors and responsive to said first and second current conditions only on said two conductors and connected to operate said second electrical means, an indicator, and means to operate said indicator from said second electromagnetic means.
